CLIP-ON FUSE INDICATOR

Filed Oct. 21, 1948

UNITED STATES PATENT OFFICE

2,492,302

CLIP-ON FUSE INDICATOR

William C. Linton, Washington, D.C.

Application October 21, 1948, Serial No. 55,773

2 Claims. (Cl. 200—121)

1

The present invention relates to lamp type indicators for all standard cartridge type enclosed electrical fuses and an object of the invention is to provide a clip-on mounting whereby an indicator may be retained upon a cartridge type enclosed fuse and yet be movable to various positions with respect to the fuse casing as requirement or conditions may dictate.

Another object of the invention is to provide a housing for lamp type indicators of a new and novel construction in which the several parts thereof may be economically constructed and assembled for reducing the costs to manufacture and thereby render the same commercially desirable.

Other objects will be in part obvious and in part pointed out hereinafter as the description continues.

In the accompanying drawings:

Fig. 1 is a side elevation of the indicator embodying the present invention as applied to a standard ferrule type cartridge enclosed fuse.

Fig. 2 is an end elevation of the same.

Fig. 3 is an end elevation of a cartridge ferrule type fuse mounted in its retaining clips with the indicator mounted along one side thereof.

Fig. 4 is a standard knife-blade type cartridge fuse with the indicator applied thereto.

Fig. 5 is an end elevation of the same.

Fig. 6 is a vertical longitudinal sectional view through the detached indicator.

Fig. 7 is a transverse section taken on the line 7—7 of Fig. 6 in the direction of the arrow points.

Fig. 8 is another transverse section taken on the line 8—8 of Fig. 6 in the direction of the arrow points.

Fig. 9 is still another transverse section taken on the line 9—9 of Fig. 6 in the direction of the arrow points.

Fig. 10 is a bottom plan view of the connecting tube, and

Fig. 11 is a bottom plan view of an end cap of the indicator housing.

The indicator as herein shown comprises a miniature neon glow lamp 1 having connected in series therewith a resistor 2 which when connected in series with the terminals of a fuse, but in parallel with the fusible element thereof will give off a visible signal as to the blown or ruptured condition of the fusible element.

The housing for this lamp indicator comprises a sectional casing constructed from a pair of cylindrical end-caps 3 connected together by means of a translucent tube 4 whereby rays of light

2

from the lamp 1 may pass therethrough and emit therefrom. The end caps 3 are preferably molded from an opaque insulating material and are identical in design and construction. The tube 4 is preferably extruded from a translucent insulating material having the same external diameter as that of the end caps 3. Each end cap has a pair of recesses 5 and 6 formed therein establishing an end wall 7 and the opposite opened end of each cap is provided with a reduced annular flange 8 capable of extending within the opened ends of the tube 4. Drive screws 9 extend through the openings 10 formed within the opposite ends of the tube 4 and the openings 11 of the flanges 8 of the end caps for rigidly connecting the same together whereby the lamp 1 may be housed within the tube 4 and one reduced end thereof extending within a recess 5 of an end cap. The resistor 2 may be positioned within the recess 5 of the other end cap having one lead wire 12 connected to a drive screw 13 whereas the other lead wire 14 of the lamp 1 is connected to another drive screw 15. These drive screws 13 and 15 extend through openings 16 formed in the end caps with their inner ends projecting within the recesses 6 whereupon the lead wires 12 and 14 may extend thereabout and be soldered thereto. The end caps 3 are each provided with a recess 17 in which is positioned a spring contact clip 18 which latter are secured to the end caps by means of the drive screws 13 and 15.

The spring contact clips 18 are each stamped from a leaf or sheet of metal, preferably beryllium copper in the shape as shown whereupon their medial arched sections when positioned within the recesses 17 of the end caps are prevented from rotating therein and the drive screws merely fasten the clips to the end caps. The outer free ends of each clip are bent upwardly and outwardly providing a pair of spaced contact points which may freely ride upon the contact terminals 19 of a cartridge fuse. The fibre cylindrical casing 20 upon which are mounted the contact terminals having a standard external diameter according to the size of the cartridge fuse and the indicator casing is retained thereupon by a single attaching clip 21.

Each attaching clip 21 is preferably stamped from a sheet of beryllium copper having an arched shaped medial section 22 attached to the tube 4 by means of a rivet 23 extending through an opening 24 formed therein. The free ends or arms 25 of each clip are bent and formed at a radius equal to the external diameter of the casing 20 of the particular fuse to which the

indicator is to be applied so as to fit snugly thereabout, but the outer extremities of the arms 25 are normally spaced apart as is best shown in Fig. 7 of the drawings and bent outwardly to permit the entrance of a fuse casing 20 therebetween. When an attaching clip is applied to the casing of a fuse the arms extend thereabout except for the spaced section between the free extremities thereof and the medial arch section 22 allows for the increased diameter of the contact terminals 19 over that of the fuse casing 20 so as to permit the spring contact clips 18 to rest upon the contact terminals 19. However, the single spring attaching clip 21 being connected equidistant from the ends of the lamp housing effects a pressure upon the clips 18 as to cause a binding contact between the clips 18 and the contact terminals 19 of the fuse, whereas the spring clips 18 being positioned at the opposite ends of the lamp housing exert a pull upon the attaching clip which causes the latter to frictionally engage the casing 20 of the fuse thereby preventing the indicator or lamp housing from freely turning upon the attached fuse casing. However, the indicator casing may be manually moved about the circumference of the fuse so that the lamp housing may be positioned at the side of a fuse or at the angle as is best shown in Fig. 5 to avoid the heads of the attaching screws usually provided and extending from the contact terminals 19 of a knife-blade type cartridge fuse. Owing to the length of the arms 25 of the attaching clips the indicator casing may be positioned at either side of a ferrule type cartridge fuse as the contact clips 18 may rest upon and contact with the outer face of the fuse retaining clips 26 as shown in Fig. 3 of the drawings.

The ferrule type cartridge fuse as shown in Fig. 1 of the drawings is of the 0-30 ampere size which have a standard length of two inches and casing of $\frac{1}{2}$ inch in diameter. The radius of the arms 25 of the attaching clip for this particular fuse should be $\frac{1}{2}$ inch or equal to the diameter of the fuse casing 20. The length of the tube 4 should be such as to prevent the end caps 3 from projecting beyond the ends of the fuse. In the manufacture of indicators for small size fuses, such as the standard midget fuse the length of the tube 4 should be reduced and the radius of the arm 25 of its attaching clip should also be reduced to the outside diameter of the casing of the midget size fuse. Likewise the length of the tube 4 must be increased and the radius of the arms 25 must be increased for each larger size fuse in order that the contact clips 18 may engage the terminals 19 thereof and the attaching clip 21 extend about the casing 20 thereof as best shown in Fig. 4 of the drawings.

From this arrangement it is apparent that during the manufacture of indicators for all standard cartridge enclosed fuses it is only necessary to cut the extruded tubes 4 to the proper length and form the arms 25 of the attaching clips to meet the particular size fuse to which it is to be applied whereas, the remaining parts

of the indicator will each be of the same size design and construction for all the different size standard cartridge enclosed fuses.

In assembling the several parts of the indicator the end caps 3 are formed with the contact clip 18 attached thereto and the tube 4 with the attaching clip 21 connected thereto whereupon the lead wire 12 of the resistor may be first soldered to the drive screw 13. The lamp 1 is then inserted within the tube 4 and its other lead wire soldered to the drive screw 15. The end caps 3 are then inserted within the opened ends of the tube 4 and the drive screws 9 inserted for connecting the tube and end caps together. The attaching clip 21 is secured to the tube 4, but may be turned or rotated upon the rivet 4 whereupon it may lie flat when the indicator is not in use to save shipping and packing space.

I claim:

1. A lamp type indicator for cartridge enclosed fuses comprising a casing consisting of a pair of end caps, a reduced portion formed with one end of each of said end caps, a translucent tube extending over the reduced portions of said end caps and secured thereto whereby the lamp may be housed therein, said end caps having recesses formed therein, spring contact clips, drive screws for connecting said contact clips to said end caps, the inner ends of said drive screws projecting within the recesses provided within said end caps, means for electrically connecting the lamp housed within said casing to the inner projecting ends of said drive screws, and clip-on means arranged intermediate of said contact clips for detachably connecting said casing to a cartridge fuse and retain said contact clips in contact with the terminals thereof.

2. A clip-on lamp type fuse indicator for cartridge enclosed fuses comprising an elongated casing housing the lamp therein, spring contact clips extending at right angles to said casing, said spring contact clips each consisting of an inverted U-shaped strip of metal each having their medial portions secured to said elongated casing, an attaching clip formed from a relatively wide strip of spring metal, an arched section formed with the medial portion of said attaching clip, means for rotatably connecting the arched section of said attaching clip to said casing intermediate of said spring contact clips, a pair of curved arms formed with and extending from the arched section of said attaching clip and the outer extremities of said arms being spaced apart to provide for the free entrance or removal of a fuse casing therebetween.
